DESIGN FOR A DISPENSER FOR A PAPER
ROLL OR THE LIKE

Frank L. Broeren, Neenah, and Archie S. Krueger,
Green Bay, Wis., assignors to Marathon Corporation, Rothschild, Wis., a corporation of Wisconsin
Application May 7, 1947, Serial No. 138,894

Term of patent 14 years

(Cl. D4—3)

To all whom it may concern:

Be it known that Frank L. Broeren and Archie S. Krueger, citizens of the United States, residing respectively at Neenah, Winnebago County, and Green Bay, Brown County, in the State of Wisconsin, have invented a new, original, and ornamental Design for a Dispenser for a Paper Roll or the like, of which the following is a specification, reference being had to the accompanying drawings, forming a part thereof.

Figure 1 is a perspective view of a dispenser for a paper roll or the like, showing our new design; Figure 2 is a perspective top plan view; and Figure 3 is a side elevational view thereof.

We claim:

The ornamental design for a dispenser for a paper roll or the like, as shown.

FRANK L. BROEREN.
ARCHIE S. KRUEGER.
